United States Patent Office

Des. 178,932
Patented Oct. 9, 1956

178,932

STORE FRONT

David Rabinowitz, Miami, Fla.

Application October 24, 1955, Serial No. 38,540

Term of patent 14 years

(Cl. D13—1)

The figure is a perspective view of a store front showing my new design.

The dominant features of my design are shown in solid lines.

I claim:

The ornamental design for a store front, as shown and described.
